(No Model.)

B. F. SINGER & M. L. DAVIS.

PERMUTATION LOCK.

No. 488,777.

Patented Dec. 27, 1892.

UNITED STATES PATENT OFFICE.

BENJAMIN FRANK SINGER AND MILES L. DAVIS, OF LANCASTER,
PENNSYLVANIA.

PERMUTATION-LOCK.

SPECIFICATION forming part of Letters Patent No. 488,777, dated December 27, 1892.

Application filed April 14, 1892. Serial No. 429,143. (No model.)

To all whom it may concern:

Be it known that we, BENJAMIN FRANKLIN SINGER and MILES L. DAVIS, of Lancaster, in the county of Lancaster and State of Pennsylvania, have invented certain new and useful Improvements in Combination-Locks; and we do hereby declare the following to be a full, clear, and exact description of the invention, such as will enable others skilled in the art to 10 to which it appertains to make and use the same.

This invention relates to improvements in combination locks of that class in which a number of ratchet wheels or tumblers are separately operated, each by a pair of pawls acting in opposite directions, so as to bring certain notches or recesses in their peripheries in line to receive a locking-bar, when the latch or lock-bolt may be readily withdrawn from its catch or holding point. 15

20 The object of the invention is to provide simple yet efficient means for securely locking doors, &c., and allowing the same to be readily opened, even in the dark, without the use of key to either drive or withdraw the bolt.

25 The purposes of the invention are attained by the mechanism and devices illustrated in the accompanying drawings, similar letters of reference designating like parts throughout 30 the several views, and in which:

Figure 1 is a plan of a door lock embodying the elements of this invention, the back-plate having been removed to expose the lock mechanism which is shown in opened or unlocked positions; Fig. 2, a top view of the portion which lies practically below the line xx in Fig. 1, the back-plate having been restored; Fig. 3, a reverse plan, partially in horizontal section, of the righthand portion of Fig. 1; 35 Fig. 4, a plan of the central portion of the righthand end of the inner or base-plate, detached from Fig. 1, the tumbler-shaft, tumblers and pawls having been removed, and four pawl-stems appearing in horizontal section; Fig. 5, an elevation from below, of the portion which lies above the line yy in Fig. 4; Figs. 6, 7 and 8, sectional elevations from the left of the central portion of the base-plate, showing the several tumblers and pairs 40 of pawls in place; Fig. 9, a sectional elevation from the right, of the portion to the left

of the line zz in Fig. 4; and, Figs. 10 and 11, similar views to Figs. 4 and 5, the parts appearing in locked positions.

A designates the case or frame-work of the 55 lock, adapted to be secured in position by means of screws passed through the orifices a in the upper and lower side walls of said case; and A' represents a circular chamber or recess which projects outward from the back- 60 plate at the righthand end of said case, and is adapted to receive and house the tubes and springs which guide and control the pawl-stems and locking-bar shaft, both of which to be hereinafter described. 65

A plate, B, practically extends over the entire inside of the case and, resting on the inner face of the back-plate, is removably secured thereto by screws b , one of which appears in each angle. This plate forms the 70 base of the invention and is adapted to support all the elements thereof, which are arranged on said plate and may be removed bodily from the case, when required. On the horizontal center line and projecting from the 75 inner face of the righthand portion of this plate are two perpendicular posts B', each having in its upper end, in the direction of said line, a U-shaped recess b' , and transversely through said end an orifice b^2 to receive a retaining pin, said posts being adapted to support the tumblers yet to be described; extending the whole way between the posts and on said center line, is a slot B², having near its center a circular orifice surrounded 80 on the outer face of the plate, by a cylindrical tube B³ provided diametrically with vertical slots b^3 , said slot and tube being adapted to receive and guide the locking-bar and its shaft, yet to be described; arranged 85 on the outer face of the plate, by a cylindrical tube B⁴ provided diametrically with vertical slots b^4 , said orifices and tubes being adapted to receive and guide the pawl-stems or shafts yet to be described; 90 projecting from the near side at the front edge of the forward post is a bridge wall B⁵ provided with an orifice b^5 adapted to receive 95 and guide the projecting end of the locking-bolt yet to be described; in the upper part 100

and projecting from the inner face of the left-hand portion of the plate are two perpendicular posts or standards B^6 , each having a rectangular orifice b^6 adapted to receive and guide the latch-bolt; projecting from the outer face, in the lower part of the forward portion of the plate, is a cylindrical post or column B^7 , through which is journaled a T-shaped handle b^7 , by means of which the latch is withdrawn or opened on the outside; in the lower lefthand corner and secured to the inner face of the plate is a pin B^{10} adapted to engage an eye to hold the lower end of a strap-spring actuating the latch in place, while a short distance diagonally forward and upward from said pin and also secured to the plate is a stop-pin b^{10} adapted to give tension to said spring; and, projecting from the inner face in the lower part of the central portion of the plate is a cylindrical column B^{11} , having in its top a screw-threaded orifice b^{11} , said column being adapted to have the inner plate attached to close the lock case.

Cylindrical tumblers formed by ratchet-wheels C , C' and C^2 are mounted to turn freely on a shaft C^3 which has its ends resting in the U-shaped recesses b' of the posts B' and secured thereto by pins c passed through the orifices b^2 in the upper ends of said posts; these tumblers, being equal in size, have in their circumferences the same number of equal divisions formed into ratchet-teeth c' across their peripheries; but in certain of these divisions are formed rectangular recesses c^2 , situated at equal intervals, differing in extent in each tumbler so that no two will be alike, and said ratchet-teeth are adapted to be engaged by the actuating pawls, while said recesses are adapted to receive the locking-bar; washers c^3 are secured, one to a side of each of said tumblers, their peripheries extending to the base of the ratchet-teeth, to form bridges for the pawls to ride on, over the recesses, c^2 , in their respective tumblers; collars c^4 are placed between the tumblers to keep them apart and allow them to be moved separately, while pin-projections c^5 from the shaft keep said collars from turning; and, collars c^6 are placed between the end tumblers and the posts to keep said tumblers in place in this direction. A pair of pawls actuate each tumbler, D above and D' below, the upper ones by pushing and the lower ones by drawing against their respective ratchet-teeth; these pawls have, each one, its rear end pivoted to a stem d resting on the plate B and, extending along said plate to its orifice, has its shaft d' passing through said orifice and through its tube B^4 , to the outside of the chamber A' , where its extremity is provided with a push-button d^2 , the tube being surrounded by a coiled spring D^2 covered by a washer d^3 held in position on said shaft, d' , by means of a pin d^4 passed through the shaft, and adapted to move back and forth in the slot b^4 , to keep said shaft and pawl from turning; and, the pawls are kept in close

contact with the tumblers by means of springs D^3 , each having its introverted ends in engagement with a pair of pawls. The pawls are here shown pivoted to the stems, d ; but these pivot joints may be omitted, and the pawls may have their rear ends rigidly connected to said stems, and their shanks thinned or flattened so as to become resilient or bending, and the spring D^3 may also be omitted; and, the shaft orifices are arranged hexagonally on the plate, B , but this is not necessary, for they may be in two parallel straight lines through the plate, and the stems may extend straight through from the pawls. These constructions embody no new invention and are so evident that their separate illustration was deemed superfluous.

A lock-bar E of approved form and strength fills the slot, B^2 , and has projecting rearward from its extremities lugs e to guide said bar as it moves into or out of said slot; across the face and cut into the front edge of this bar, are recesses e^2 to receive the tumbler-washers when said bar is pushed into the tumbler recesses; integral with the lefthand end of this bar is a side projecting lug or arm e^3 adapted to move behind the end of the locking-bolt to keep the latch-bolt or lock closed, and to rise above said bolt-end when said latch-bolt or lock is opened; projecting rearwardly and centrally from the back of this bar and having one end integral therewith, is a shaft e^4 , which, passing through the central orifice and through its tube B^3 , to the outside of the chamber, A' , has its other end provided with a push-button e^5 , the tube being surrounded by a coiled spring E' , covered by a washer e^6 , secured to the shaft, e^4 , by means of a pin e^7 passed through the shaft, and adapted to move back and forth in the slots, b^3 , of the tube; and, toward one end, in the back of this bar, is formed a recess e^8 , to receive and hold in place a dead-latch bolt, O , operated through a side of the lock-case, by a handle o , and said bolt is adapted to keep said bar within the tumbler recesses, holding the lock opened.

In line with and extending forwardly from the posts B' , and resting on the plate B , is a slide-bolt F , having vertically through its body a longitudinal slot f , through which a flat-headed screw F' serves to secure said bolt to the plate, keeping it sidewise in place, and the slot f allowing it to move back and forth; projecting from the lower portion of its rear end, is a rearwardly extending arm or shaft f' adapted to move freely back and forth through the guide orifice b^5 , and having a prescribed length has its rear extremity adapted to impinge against the arm e^8 of the lock-bar to securely lock or hold the latch-bolt closed; in the forward portion of the lower edge of this bolt are a number of gear-teeth f^2 forming a rack by means of which the engaging teeth of a pinion F^2 secured to the inner end of the shaft of the T-shaped handle b^7 , serve to move said bolt back and forth from the

outside, of course the bar E must be in the position indicated in Figs. 4 and 5; and, near the forward end, in the upper edge, is a pin f^3 adapted to engage a lug or projection from the shaft of the latch-bolt, by means of which said latch-bolt is withdrawn from its catch.

An ordinary latch-bolt G has its shaft g fitted into the orifices b^6 of the posts B^6 , and is adapted to rest in, as well as to be moved back and forth in said orifices; the forward end of this latch-bolt has a widened head g' provided with the usual slope allowing it to ride readily into its catch (not shown); behind this head is a recess g^2 , placed into the body of the bolt, to receive and retain the upper or free end of the actuating spring yet to be described; on the under side of this bolt, leaving sufficient space to allow the bolt to move forward the required distance, and rigidly secured to its shaft, or integral therewith, is a cross-beam or bar G' , forming side projections, g^3 and g^4 , extending beyond the front and rear edges of said shaft,—the rear one g^3 , being adapted to be engaged by the pin f^3 of the bolt F, by means of which engagement, said bolt F and said latch G, mutually move each other; and, the front one, g^4 , has attached to its under side, a strip or bar G^2 provided on its under side with gear-teeth g^5 , forming a rack by means of which a pinion operated from the inside, serves to withdraw said latch-bolt, independently of the locking device before mentioned.

In the forward portion of the lock-case, is a strap-spring H, having at its lower end an eye h , through which the pin B^{10} holds said end in place; after passing obliquely upward, in front of the stop-pin b^{10} which gives it tension, and having its upper or free end in the recess g^2 of the latch-bolt G, said spring is adapted to keep said latch-bolt pressed forward, or its head in engagement with its catch.

The entire back of the case, between its upper and lower side walls is covered by a plate I, having its ends resting against the end walls of said case, and its body against the end or head of the column B^{11} , and secured thereto by a flat-headed screw i , having its shank passed through the plate and screwed into the orifice b^{11} thereof; projecting from the back of this plate and at a prescribed point, is a boss I' , having journaled through its center the shaft of a T-shaped handle i' , to the inner end of which is affixed a gear-wheel or pinion I^2 , whose teeth intermeshing with those of the rack G^2 , are adapted to move back or withdraw the latch-bolt from within.

The parts all being in the several positions indicated in Figs. 1 and 2, and the spring H having moved the latch-bolt G, and, by reason of the contact of the lug g^3 with the pin f^3 , the bolt F, to the dotted positions, the lock may be readily opened, either from the inside or from the outside by simply turning the handle b' , or the handle i' , and the action of the spring H will always return both latch

and bolt to said dotted positions. Now, moving the dead-latch O backward in its recess e' , to the position indicated in Fig. 10, the action of the spring E' (Fig. 2), will move the bar E to the position indicated in Fig. 11, and pass the arm e^3 of said bar, behind the end of the shaft f' , when the bolt F will be locked in position and thus prevent the latch G from being opened, or moved back, from the outside, but this will not prevent the handle i' to freely move said latch, from the inside. Again, should any one of said tumblers, or all of them, now be turned, even to the extent of one ratchet-tooth only, the line of recesses c^2 will be broken or moved from the position indicated, and the bar E with the locking-arm e^3 cannot be moved forward to release the bolt F; or, the lock cannot again be opened from the outside, without first restoring said line of recesses c^2 to the position in front of and opposite to, the bar E, and best shown in Figs. 6, 7 and 8, it being remembered that the bar E was withdrawn from said recesses, c^2 , into the slot B^2 by its spring E'. Referring, now, to these figures, it will be observed that the pawls are all in their normal positions, that is, having their stems, d , resting against the plate, B; that the upper pawls, D, have their points in position to engage the first ratchet-tooth behind the vertical center line 1, in each figure, while the lower pawls, D', are in position to engage the first ratchet-tooth in front of said center line; this arrangement being necessary to enable one or other pawl of the same wheel to always engage a ratchet-tooth, either above or below in the periphery of said wheel; and, that each push upon the button, d^2 , of each pawl, in the direction indicated by the arrows, 2, will rotate the particular ratchet-wheel or tumbler forward, the space of one notch or tooth, in the direction indicated by the arrows, 3. Now, considering the tumbler, C (Fig. 6), its position shows, that when a recess c^2 is in position to receive the bar E, the pawl D rests in the second notch or tooth from the recess c^2 it just passed, hence it follows that when a pawl D is done pushing, having brought a recess c^2 to the top or vertical center line, the recess c^2 in question, will be the space of two ratchet teeth short from the required position to receive the bar E, and the pawl D' is required to complete the movement of the tumbler. Again, considering the tumbler C' (Fig. 7), its position shows that when a recess c^2 is in position to receive the bar E, the pawl D rests in a recess c^2 , hence it follows that when the pawl D is done pushing, having brought a recess c^2 to the top or vertical center line, the recess c^2 in question will be in the position to receive the bar E, and the services of the pawl D' will not be required. And, considering the tumbler C² (Fig. 8), the same observations will hold, as in the case of the tumbler C, second before mentioned, except that the pawl D need not be pushed as often, but the pawl D' will have to be pushed twice, as in the case of the tumbler, C.

It remains now only to show how the opening line of recesses c^2 may be established from any position of the different tumblers. Bearing in mind the facts recited in the preceding paragraph, the buttons d^2 moving the pawls D must be pushed, each one, a number of times equal to the number of ratchet teeth in the interval between the recesses c^2 of the tumbler said pawl is to move; and then the buttons d^2 moving the pawls D' must be pushed, twice for each one of the tumblers C and C' (Figs. 6 and 8), while the tumbler C' (Fig. 7) need not be further moved, it having been brought into position by the pawl D, as previously shown.

Having now described the invention, what we do consider new and desire to secure by Letters Patent, is:—

1. In a combination-lock, the herein described tumbler, comprising a ratchet-wheel having in its periphery a number of recesses c^2 at equal intervals apart, the same number of ratchet-teeth in each of said intervals, and a washer secured to a side of said ratchet-wheel, said washer having its periphery at the base of said ratchet teeth; said tumbler adapted to be mounted upon a shaft, and mechanism provided to rotate the tumbler whereby any recess c^2 may be brought to the opening line, substantially as described and for the purpose set forth.

2. In a combination lock, having a frame or case A as described, the base plate B possessing the following functional elements: the perpendicular posts B' and B', U-shaped recesses b' in the upper ends of said posts, orifices b^2 transversely through said upper ends, said posts on the horizontal center line, projecting from the inner face in the right hand portion of the plate; the longitudinal slot B² through the body of the plate, on said center line between said posts, said slot having the central shaft-orifice surrounded by the tube B³ having the slots b^3 projecting from the outer face of the plate; the tumbler shaft-orifices through the body of the plate and surrounded by the tubes B⁴ having the slots b^4 , said tubes projecting from the outer face of the plate; the bridge-wall B⁵ having the guide-orifices b^5 projecting from the front edge of the forward post B' and from the inner face of the plate; the perpendicular posts B⁶ and B⁶ having the guide orifices b^6 projecting from the inner face in the upper left hand portion of the plate; the perpendicular column B⁷, through the axis of which is journaled the T-shaped handle B⁷, projecting from the outer face in the lower left hand portion of the plate; the pin B¹⁰ and the pin B¹⁰ projecting from the lower left hand corner of the plate; the perpendicular column B¹¹ having the screw-threaded orifice b^{11} in its top, projecting from the inner face in the lower left hand portion of the plate; and means provided on the horizontal center line to hold and guide a slide-bolt in place; said plate and all its contained elements made integral, forming one body

adapted to support the mechanism of the lock, to cover the base of the lock case and to be removably secured thereto, all substantially as described and for the purpose set forth.

3. The combination in a combination lock having a case A as described, with the plate B, as described, secured in position within the body of said case, said plate having the posts B' as described projecting from the inner face on the horizontal center line in the right hand portion of the plate, of the ratchet-tumblers C, C' and C² as described, the shaft C³ passed through the axes of said tumblers, 80 the extremities of said shaft in the U-shaped recesses b' of said posts and secured thereto by the pins c, the collars c⁴ and c⁴ between the tumblers, and the collars c⁶ between the end tumblers and the posts, and mechanism 85 provided to rotate said tumblers, all substantially as described and for the purpose set forth.

4. The combination in a combination lock having a case A as described, with the plate B having the posts B' as described, said plate removably secured to within the body of the case, and the ratchet tumblers C, C' and C² as described, said tumblers mounted as described upon the shaft C³ supported by the posts B' as described, of a pair of pawls to each tumbler, D above and D' below, said pawls having their forward ends to engage the ratchet teeth of the tumblers, and their rear ends pivoted to the stems d having their shafts d' passed through the orifices in the plate and through the surrounding tubes B⁴, the springs D² surrounding said tubes and secured to said shafts by the washers d³ and the pins d⁴ passed through the shafts and 105 movable in the slots b⁴ of the tubes, the springs D³ having their introverted ends to press upon the forward ends of the pawls, and the push-buttons d² secured to the outer ends of the pawl-shafts d', all substantially as described and for the purpose set forth.

5. The combination in a combination lock such as described, having the plate B removably secured in position as shown; the ratchet tumblers C, C' and C² as described, said tumblers mounted upon the shaft C³ supported by the posts B' of the plate, and mechanism provided to rotate the tumblers; and the slot B² as described through the body of the plate between the posts; with said tumblers, each having the peripheral recesses c^2 at equal intervals apart in the same tumbler, said intervals being unequal in the different tumblers, of the locking-bar E in the slot B², the guide lugs e projecting rearward from the ends of said bar, the recesses e² across and in the front edge of said bar, the side-lug e³ having its rear end integral with the front ends of said bar, the shaft e⁴ having its front end secured to the back of the bar, said shaft passed 120 through the central orifice and the tube B³ of the plate to the outside of the lock, the push-button e⁵ secured to the end of the shaft, the spring E' surrounding the tube B³ and se-

cured to the shaft e^4 by the washer e^6 and the pin e^7 passed through the shaft, and movable in the slot b^8 of the tube, and, means provided such as the dead-latch O to hold the bar in engagement with the recesses c^2 of the tumblers as shown, all substantially as described and for the purpose set forth.

In testimony whereof we have hereunto sub-

scribed our names in the presence of two subscribing witnesses.
